UNITED STATES PATENT OFFICE

GEORGE W. FROST, OF SPRINGFIELD, ILLINOIS

AWNING

Application filed September 24, 1928. Serial No. 307,849.

My invention relates to awnings of that type wherein the awning fabric is wound on a roller at the top of the window and has for one of its objects the provision of certain improvements in the construction and operation of the same whereby the device is extensible and may be applied to window frames of various heights with a minimum of effort and the arrangement be such that the awning may be manipulated from the interior without the necessity for raising or lowering sashes or the screens which may be in position.

Another object of the invention is the provision of an awning which is easy to operate and noiseless in operation, the mounting being of such character that strong winds do not whip the awning.

Still another object is the provision of an awning roof or hood which is extensible and adapted for use with windows of various widths.

A hood or roof will be most effective when it is mounted in as close proximity to the rolled up awning as is feasible without interfering with the rolling or unrolling of the awning. In practice it is found difficult to thus accurately position the hood with reference to the rolled up fabric in order that it may be spaced sufficiently to avoid interference with the fabric and yet be sufficiently close to prevent the wind from driving rain, sleet or the like under the hood, and another object is to provide means whereby the device when assembled requires the hood to take a predetermined position and slope sufficiently close to the awning which it shelters to prevent rain, sleet or snow from being driven therein and be spaced away sufficiently not to interfere with the rolling and unrolling operations.

A further object of the invention is to provide an awning which is neat and compact when rolled up and which has a hood capable of protecting fabric so that winter storage is unnecessary and the life of the fabric is increased.

A still further object is the provision of an awning and mounting therefor which is light and durable. The invention has

among its other objects the production of a device of the kind described which is extremely neat and attractive in appearance, simple, convenient, compact, durable, reliable, efficient and satisfactory for use wherever found applicable.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a perspective view of a window equipped with the device of my invention in which the awning is shown in its lowermost position;

Fig. 2 is a view along line 2—2 of Fig. 1 drawn to a larger scale;

Fig. 3 is a sectional view upon line 3—3 of Fig. 2;

Fig. 4 is a sectional view on line 4—4 of Fig. 2;

Fig. 5 is a view on line 5—5 of Fig. 2;

Fig. 6 is a view on line 6—6 of Fig. 5;

Fig. 7 is a detail of a connection of one end of the frame to a guide member;

Figs. 8 and 9 are perspective views of sections comprising the guide member; and

Fig. 10 is an enlarged perspective view of one of the end closures formed on the hood, and illustrating the portions associated with the closure adapted to cooperate with the roller supporting bracket member for determining the position of the hood with respect to the bracket member.

Referring to the drawings, an awning fabric 10 is shown as mounted upon a roller 11, the roller being adapted to roll and unroll the fabric to different lengths. The roller 11 is mounted upon brackets 12 which project from guide members 13, fastened on the sides of the window frame. The guide member 13 is made up of two overlapping

sections, preferably L-shaped and adjustably fastened together for a purpose hereinafter more particularly described. A stay rod 14 extends transversely of the fabric between its end portions and is fastened to the fabric by a seam or any other desired means. The ends of the stay rod 14 lie behind the outstanding leg of the guide members 13 when the awning is in extended position. The rod 14 is rolled up with the fabric when the awning is in its closed position. The outstanding leg 15 of the guide member 13 stops short of the roller 11 at its upper end and is turned outwardly to deflect the stay rod 14 as it is unrolled with the fabric and to guide the rod into the space back of the legs 15.

The stay rod 14 is provided at each end with roller bearings comprising an exteriorly threaded sleeve 36 which engages an interiorly threaded ferrule-shaped roller 37. The rod 13 fits loosely in the sleeve 36 and has its ends expanded to prevent the bearings from slipping off the end of the rod. The sleeve 36 thereby provides a journaled mounting for the rod 14. When the rod 14 is raised or lowered, the bearing rotates in contact with the outstanding leg of the guide member 13, thereby eliminating friction which would otherwise result from a sliding contact between the rod 14 and the guide member 13.

A U-shaped frame 16 is connected to the lower end of the guide members 13 by pivotally mounting the free ends of the arms of the frame in brackets 17 provided for that purpose on the lower end of the guide members. The frame 16 is fastened to the awning fabric 10 near the lower end of the fabric whereby the extreme end portion of the fabric forms a flap 18 which is suspended from the frame for all extended positions of the awning.

The rolled portion of the awning fabric 10 is protected from the weather by a hood 19 which is mounted on the window frame immediately above the roller 11 and spaced therefrom sufficiently to permit the entire fabric to be rolled without coming in contact with the hood. The hood 19 is preferably arcuate in section, sloping downwardly and outwardly so that the front edge of the hood is substantially opposite the mid portion of the roller, in which position it provides protection against driving rain, sleet, snow or the like. The hood 19 comprises two overlapping longitudinally extending sections 20 and 21, the edges of which are curved inwardly so that the section 20 is telescoped within the section 21. The hood 19 is thereby made extensible in length to fit any width of window frame. Downwardly extending plate members 22 and 23 mounted on the members 20 and 21 respectively provide end closures which

prevent rain or snow from entering the case of the hood.

The plates 22 and 23 are offset outwardly near their mid portion to provide clearance for the ends of pins 35 upon which the roller 11 is mounted and thereby enables the plates to more snugly fit and enclose the roll of enclosed awning fabric.

The plates 22 and 23 are positioned between the adjacent guide member 13 and the side frame of the window. The member 13 is provided with an aperture 33 near its upper end which registers with corresponding apertures 22a in the members 22 and 23 and through which screws 24 are driven into the window frame when the device is assembled.

The hood is most effective as a roof for the roller fabric when positioned close to the roll, and in order that the space between the exterior of the roll and the hood be sufficient to prevent interference when the awning is rolled up and still be as close as possible, I have provided a stop 25 against which the end of the guide member 13 rests when the members 13 are fastened to the plates 22 and 23 by means of the screws 24.

The position of the stop 25 in contact with the end of the guide member section 13a and the predetermined position of the hole 33 in the member 13a, which registers with a hole in the end closures of the hood, serve to fix not only the spacing of the hood from the rolled fabric but also determines the slope of the hood. By properly determining the position of the stop 25 and the registering apertures through the closure and the guide member I am enabled to predetermine the most advantageous slope and position for the hood and roof and provide for its assembling and erection only in such advantageous position regardless of the skill or experience of the erector.

The awning fabric is unrolled by means of a cord 26 which is fastened to the fabric at the mid portion of the rod 14, and is rolled up with the end portions of the fabric which extend beyond the rod. The fabric is unrolled by pulling the cord 26 downwardly, thereby carrying with it the rod 14 over the curved member 15 and back into a runway provided by the outstanding legs of the guide members 13. The outer end of the U-frame 16 rests against the rolled fabric underneath the hood 19 when the awning is completely raised, and in the operation of lowering the awning by pulling on the cord 26 the frame 16 tilts downwardly and outwardly to the completely lowered position shown in Fig. 1. The roller 11 is a spring roller and the operator in opening the awning pulls against this tension which is constant and continuous. In the event that it is not desired to open the awning completely, the awning may be

fastened in any such partially opened position by fastening the cord 26 to a staple 45 or the like which is mounted in the casing or sill of the window. A lug 27 formed on the extreme end of the arms of the frame 16 serves as a stop to limit the amount of downward movement of the frame 16 and of the inclined end portion of the awning. The outstanding leg of the lower portion of the 10 guide member 13 is turned inwardly to provide a stop 28 limiting the amount of downward motion of the rod 14. The rod 14 comes in contact with the stop 28 substantially simultaneously with the contact 15 of the lug 27 with the head of one of the rivets 29 by means of which the bracket 17 is fastened to the guide member 13.

The awning is adapted for mounting in windows of varying depths, as well as of 20 different widths, and for this purpose the guide member 13 is made extensible by constructing it in two sections, an upper section 13a and a lower section 13b which when assembled are in overlapping relation. The 25 upper section 13a is shown in perspective in Fig. 9 and has its outstanding leg perforated to form a plurality of slots 30. The other leg of the section 13a has a hole 31 near its lower end. The lower section 30 13b is shown in perspective in Fig. 8 and is provided with a plurality of equally spaced holes 32 in its outstanding leg, the spacing of the holes being preferably the same as the spacing of the slots 30. The 35 hole 31 is so positioned as to register with one of the holes 32 in the short leg of the member 13b when the members 13a and 13b are fastened together. The members 13a and 13b are connected in overlapping relation by a laterally and longitudinally extending element or stem 43 which is provided on the upper end of the outstanding leg of section 13b for insertion in any one of the apertures 30 in the outstanding leg 40 of the member 13a. By inserting the stem 43 in any one of the apertures 30, the sections 13a and 13b are locked together with the hole 31 in register with a corresponding hole 32. When the members 13a and 13b 45 are thus assembled, in accordance with the height of the window, the guide member 13 thereby formed is ready for fastening to the window casing. This fastening is accomplished by means of the screw 24 which extends through the end member of the hood and through the aperture 33 in the upper end of the section 13a and by a second screw 40 which extends through the hole 31 and the particular hole 32 with which the 50 hole 31 then registers and by a third screw 41 which is inserted in the hole 34 in the lower end of the section 13b, thereby providing for fastening the extensible member 13 to the window casing in any desired lengths.

Having thus described my invention, it

is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described, an awning, a stay rod for the awning, and a pair of vertically extending guide members for the stay rod, said guide members each comprising two overlapping sections, and cooperable means formed on the respective sections for fastening said sections together in any one of a plurality of overlapping positions.

2. In a device of the class described, an awning, a stay rod for the awning, and a pair of vertically extending guide members for the stay rod, said guide members each comprising two overlapping sections, and means for fastening said sections together in any one of a plurality of overlapping positions, said means comprising a plurality of spaced apart apertures in one of said sections and a projecting element on the other section, said element being adapted for locking engagement with said first mentioned section by insertion in any one of said apertures.

3. In a device of the class described, an awning, a stay rod for the awning, a pair of vertically extending guide members each comprising two overlapping L-sections and interengaging means for fastening corresponding legs of said sections together in any one of a plurality of overlapping positions.

4. In a device of the class described, a roller, an awning fabric secured to the roller and adapted to be wound thereon, a stay rod attached to the awning fabric, vertical guide members on the sides of the window frame behind which the ends of said stay rod lie when the awning is in extended position, said guide members each comprising two sections in overlapping relation, and interlocking means formed on the respective sections for fastening said sections together in various overlapping positions whereby said guide members are extensible and adapted for mounting in windows of different heights.

5. In a device of the class described, an awning, a stay rod for the awning, a pair of vertically extending guide members each comprising two overlapping L sections and means for fastening corresponding legs of said sections together in any one of a plurality of overlapping positions, said means comprising a plurality of spaced apart apertures in that leg of one section adapted for

fastening to a window frame, a single aperture in the corresponding leg of the other section, said apertures being adapted to receive wood screws for attachment to the window frame, an offset stem on one end of the outstanding leg of said first mentioned section, a plurality of apertures in the corresponding outstanding leg of the other section, said last mentioned apertures being adapted to receive said stem in interlocking engagement and being spaced similarly to said first mentioned apertures and so positioned that when said stem is inserted in an aperture in the outstanding leg, said single aperture is in register with one of said first mentioned plurality of apertures for the purpose described.

6. In a device of the class described, a roller, an awning fabric wound on the roller, 20 bracket members forming supports for the roller, a hood overhanging said roller, and closures on the hood connected to said bracket members, said closures having elements forming part thereof which predetermine the angle of inclination of the hood and the space between the hood and the roller, 25 said elements comprising a stop and an aperture, said stop abutting the end of said bracket member and said aperture being in register with a corresponding aperture in 30 the bracket member when the device is assembled.

7. In a device of the class described, a roller, an awning fabric wound on the roller, 35 a stay rod attached to the awning fabric, guide members behind which said stay rod moves when the fabric is rolled and unrolled and on which said roller is mounted, a hood mounted above the rollers, said hood having end closures in contact with said 40 guide members, and a stop on the end closures cooperable with said members for determining the position of the upper ends of the guide members.

45 8. In a device of the class described, a roller, an awning fabric wound on the roller, a stay rod attached to the awning fabric, guide members behind which said stay rod moves when the fabric is rolled and unrolled 50 and on which said roller is mounted, a hood mounted above the rollers, said hood having end closures in contact with said guide members, said closures and guide members having apertures which register for a predetermined slope of said hood for the 55 purpose described.

9. In a device of the class described, a roller, an awning fabric wound on the roller, bracket members forming supports for the 60 roller, a hood overhanging said roller, and closures at the ends of said hood connected to said bracket members, said closures having portions forming part thereof and cooperable with said bracket members for 65 determining the position of said hood with

respect to said bracket members and roller. In testimony whereof, I have hereunto signed my name.

GEO. W. FROST.
